The ornamental design for a lozenge, as shown and described.

DESCRIPTION

FIG. 1 is a top perspective view of a lozenge showing the new design, according to a first embodiment;

FIG. 2 is a top plan view of the lozenge;

FIG. 3 is a side elevational view of the lozenge, it being understood that all side views of the lozenge are identical;

FIG. 4 is a bottom perspective view of the lozenge;

FIG. 5 is a bottom plan view of the lozenge;

FIG. 6 is a top perspective view of a lozenge showing the new design, according to a second embodiment;

FIG. 7 is a top plan view of the lozenge;

FIG. 8 is a side elevational view of the lozenge, it being understood that all side views of the lozenge are identical;

FIG. 9 is a bottom perspective view of the lozenge; and,

FIG. 10 is a bottom plan view of the lozenge.
